UNITED STATES PATENT OFFICE.

ALFRED WILKINSON, OF BRIDGEPORT, PENNSYLVANIA, ASSIGNOR TO THE WILKINSON MANUFACTURING COMPANY, INCORPORATED, OF BRIDGEPORT, PENNSYLVANIA, A CORPORATION OF PENNSYLVANIA.

GRATE-BAR.

No. 817,028.

Specification of Letters Patent.

Patented April 3, 1906.

Application filed April 28, 1905. Serial No. 258,050.

To all whom it may concern:

Be it known that I, ALFRED WILKINSON, a citizen of the United States, and a resident of Bridgeport, Pennsylvania, have invented certain Improvements in Grate-Bars, of which the following is a specification.

My invention consists of certain improvements in grate-bars of the character shown in my previous Letters Patent, Nos. 480,538, 541,405, and 541,448, the objects of my present invention being to provide for the convenient formation of air-holes and twyer-openings in the fuel-supporting surface of the grate and to provide for the ready renewal of any defective portion of a grate-bar without necessitating renewal of other portions of the same. These objects I attain in the manner hereinafter set forth, reference being had to the accompanying drawings, in which—

Figure 1 is a perspective view of a grate-bar constructed in accordance with my present invention. Fig. 2 is a longitudinal section of the same. Fig. 3 is an enlarged longitudinal section of part of the bar. Fig. 4 is an enlarged perspective view of one of the units of the fuel-supporting surface of the bar. Fig. 5 is a side view of the same on a still larger scale. Fig. 6 is a transverse section on the line *a a*, Fig. 3; and Fig. 7 is a sectional plan view, on an enlarged scale, on the line *b b*, Fig. 3.

The grate-bar has a stepped fuel-supporting surface, as in the bars previously employed in my automatic stoker, this stepped surface having twyer-openings in the risers of the steps and the bar also having in the present instance air-holes in what may be termed the "treads" of the steps—that is to say, the portions upon which the bed of fuel rests. Each of the steps is also in the present bar an independent unit applicable to and removable from the top of the bar. The grate-bar consists of a hollow trough-like body portion 1, open at the top, and a perforated fuel-supporting portion mounted upon and extending across said open top of the body portion. The trough-like body portion is open at the top, the upper edges of the opposite side walls of the same presenting an inclined plane 2, and each of said walls having on its inner face a horizontal groove or recess 3, extending out to

the inclined upper edge of said side wall, as shown in Fig. 3. The fuel-supporting portion of the bar is composed of a plurality of twyer-plates 4, each with a number of perforations 5 therein and each having a depending front flange 6 with notch 7 in its lower edge. Each of the twyer-plates 4 also has a depending side flange 9 with inclined lower edge for resting upon the inclined upper edge of the side wall of the body portion of the grate-bar when the upper face of the twyer-plate 4 occupies a horizontal position, as shown in Fig. 2. The rear portion of each twyer-plate 4 is contracted in width, as shown in Fig. 7, so that it may fit between the opposite side walls of the body portion of the grate-bar and may enter the recesses or grooves 3 formed therein, the rear edge of the twyer-plate being notched, as at 10, Figs. 4 and 7, so as not to interfere with the free access of the air to a twyer-plate above the same. The depending front flange 6 of each twyer-plate rests upon the upper face of the twyer-plate below it, and in order to prevent horizontal dislodgment of one twyer-plate in respect to the other each twyer-plate has projecting from its upper face at each edge a lug 11 for bearing upon the depending front flange of the following plate, the rear faces of the lugs being undercut, as shown in Fig. 5, so as to overlap the beveled front of the flange 6 and also prevent vertical displacement of the same. Further provision against horizontal displacement of each twyer-plate is afforded by lugs 12 on the under side of each plate, which lugs enter notches 13 in the bases of the grooves 3. When a grate-bar thus equipped has air under pressure forced into the same, said air escapes into the mass of fuel both from the twyer-openings 5 in the horizontal portions of the plates and also from the twyer-notches 7 in the front flanges of the same. Hence an ample supply of air for maintaining combustion of the fuel is insured.

The lowermost twyer-plate 4 is locked in place by means of a nut on a hooked bolt 15, which engages a lug at the bottom of the body portion of the bar, and this serves also to lock the other plates in place when the bar is in use. When this plate has been removed,

however, the twyer-plates above the same can also be readily removed by simply raising the forward edge of a plate until its lugs 12 are free from engagement with the notches 13, the plate being then drawn outwardly, and a new plate can be readily inserted by a reversal of these operations, so that any burned, worn, or otherwise defective part of the fuel-supporting surface of the bar can be 10 readily renewed without necessitating the renewal of any other part of said surface.

The upper portion of the trough-shaped body portion of the bar is stiffened and strengthened by means of transverse brace- 15 rods 16, cast with the bar. (See Fig. 2.)

Either the perforations 5 or the notches 7 may be omitted, if desired; but the use of both is preferred.

Having thus described my invention, I 20 claim and desire to secure by Letters Patent—

1. A grate-bar comprising a trough-shaped body portion open at the top and a fuel-sup- 25 porting portion consisting of a series of per- forated twyer-plates independently mounted upon said body portion of the bar so as to overlap, and extending across the open top of said body portion, each plate being pre- 30 vented from moving either longitudinally or transversely in a horizontal plane by engage- 35 ment with the sides of the body portion of the bar, substantially as specified.

2. A grate-bar comprising a trough-shaped body portion open at the top, and a fuel-sup- 35 porting portion consisting of a series of per- forated twyer-plates independently mounted upon said body portion of the bar so as to overlap, and extending across the open top of said body portion, each plate, except the 40 lowermost, being locked in position against horizontal displacement by engagement with the plate below and also by engagement of a portion of it with the sides of the body portion of the bar, substantially as specified.

3. A grate-bar comprising a trough-shaped body portion open at the top, and a fuel-sup- 45 porting portion consisting of a series of per- forated twyer-plates independently mounted upon said body portion of the bar so as to overlap, and extending across the open top of said body portion, each plate, except the 50 uppermost, being locked in position against vertical displacement by engagement with the plate above and also by engagement with the sides of the body portion of the bar, sub- 55 stantially as specified.

4. A grate-bar comprising a trough-shaped body portion open at the top, and a fuel-sup- 60 porting portion consisting of a series of per- forated twyer-plates independently mounted upon said body portion of the bar so as to overlap, and extending across the open top of said body portion, each plate, except the 65 lowermost, being locked in position against vertical displacement by engagement with

the plate below, and also by engagement with the sides of the body portion of the bar, sub-stantially as specified.

5. A grate-bar comprising a trough-shaped body portion open at the top, and a fuel-sup- 70 porting portion consisting of a series of per- forated twyer-plates independently mounted upon said body portion of the bar so as to overlap, and extending across the open top of said body portion, each plate, except those 75 at the ends of the series, being locked in position against vertical displacement by en-gagement with the plates above and below it, and also by engagement with the sides of the body portion of the bar, substantially as 80 specified.

6. A grate-bar comprising a trough-shaped body portion open at the top, and a fuel-sup- 85 porting portion consisting of a series of per- forated twyer-plates independently mounted 85 upon said body portion of the bar so as to overlap, and extending across the open top of said body portion, each plate, except the lowermost, having a front flange resting upon the top of the twyer-plate below and the lat- 90 ter having lugs for engaging said flange, sub-stantially as specified.

7. A grate-bar comprising a trough-shaped body portion open at the top, and a fuel-sup- 95 porting portion consisting of a series of per- forated twyer-plates independently mounted upon said body portion of the bar so as to overlap, and extending across the open top of said body portion, each twyer-plate, ex- 100 cept the lowermost, having a front flange resting upon the top of the twyer-plate be- 105 low, and the latter plate having lugs for en-gaging said flange and being also provided with means for locking it to the sides of the body portion of the bar against horizontal 110 displacement, substantially as specified.

8. A grate-bar comprising a trough-shaped body portion open at the top, and having side walls with inclined tops and grooves in 115 the inner faces of said side walls extending rearwardly from the inclined tops, and a fuel-sup- 120 porting portion consisting of a plurality of twyer-plates, each extending across the open top of the body portion of the bar and 125 engaging certain of said grooves, and each 130 having side flanges with beveled lower edges resting upon the inclined tops of the side walls, substantially as specified.

9. A grate-bar comprising a trough-shaped body portion open at the top and having side 120 walls with grooves in the inner faces said 125 grooves having notched bottoms, and a fuel-sup- 130 porting portion consisting of a plurality of twyer-plates extending across the top of the body portion of the bar, and each engag- 135 ing the notched bottoms of certain of said grooves, substantially as specified.

10. A grate-bar comprising a trough- 130 shaped body portion open at the top and having side walls with grooves in their inner 135

faces, and a fuel-supporting portion consisting of a plurality of twyer-plates extending across the open top of the body portion of the bar, and each having a front portion with flanges resting upon the tops of the side walls and a rear portion of contracted width engaging with grooves in the inner faces of said walls, substantially as specified.

In testimony whereof I have signed my name to this specification in the presence of 10 two subscribing witnesses.

ALFRED WILKINSON.
